COMBINED STRAIGHT EDGE AND PEN HOLDER

Leo R. Slaton, Chicago, Ill., assignor to Swiss Harmony, Inc., Chicago, Ill., a corporation of Illinois

Application April 23, 1958, Serial No. 50,590

Term of patent 7 years

(Cl. D52—1)

Fig. 1 is a top perspective view of a combined straight edge and pen holder embodying my new design;

Fig. 2 is a bottom plan view of the same; and

Fig. 3 is an enlarged sectional view taken substantially along the lines 3—3 of Fig. 1.

I claim:

The ornamental design for a combined straight edge and pen holder, as shown.
